(57) **CLAIM**

The ornamental design for a “collapsible bench with canopy,” as shown and described.

DESCRIPTION

FIG. 1 is a front view of the bench in an expanded position; FIG. 2 is a rear view of the bench in an expanded position; FIG. 3 is a right side view of the bench in an expanded position;

FIG. 4 is a left side view of the bench in an expanded position; FIG. 5 is a top view of the bench in an expanded position; FIG. 6 is a bottom view of the bench in an expanded position; FIG. 7 is a perspective view of the bench in an expanded position;

FIG. 8 is a perspective view of the bench in a collapsed position;

FIG. 9 is a perspective view of a variant of the bench in an expanded position; and,

FIG. 10 is a exploded perspective view detailing the feet support of the bench in the expanded position.

The broken lines shown in the drawings are for illustrative purposes only and form no part of the claimed design.
